HARALD SMITH, OF COPENHAGEN, DENMARK.

VIBRATION-TRANSFERRING MEANS.

1,313,751.

Specification of Letters Patent.

Patented Aug. 19, 1919.

Application filed August 23, 1916. Serial No. 116,425.

To all whom it may concern:

Be it known that I, HARALD SMITH, a subject of the King of Denmark, residing at Copenhagen, Denmark, at 1^a Tranevei, have 5 invented certain new and useful Improvements in Vibration-Transferring Means, of which the following is a specification.

The invention relates to vibration transferring means.

10 More particularly, the invention is directed to means for transferring vibrations from one diaphragm, or equivalent element, to another diaphragm or equivalent element. A form of the invention applicable for use 15 with a telephone receiver comprises a hollow symmetrical member having an opening of predetermined cross section and having its body portion attached or otherwise secured to the diaphragm or equivalent member, de- 20 sired to be actuated in correspondence to the vibrations of the diaphragm of the telephone receiver, and further comprising an element having a body portion projecting through said opening and having a cross section and 25 constructed to effect the frictional engagement with the sides of said opening and fur- 30 ther having a forward portion adapted to engage or be held into engagement with the actuating diaphragm of the telephone re- ceiver. The frictional engagement between 35 the body portion of said element and the sides of the opening in said member is of such degree that the vibrations are trans- 40 ferred without interference for all relative positions between said member and said ele- 45 ment.

The invention is applicable for all other types of electro responsive devices as well as telephone receivers and the diaphragm, or 40 equivalent, may form a part or combine with an amplifier, relay, repeater or the like.

The invention is also applicable for use with the receiving device of an amplifier in conjunction with a dictating talking ma- 45 chine or other type of acoustic machine. In such arrangement, the amplified "sounds" emitted by the diaphragm of the receiving device are transferred to the diaphragm of the talking machine and the recording stylus 50 of the same actuated to record the message or conversation onto the record. In such form of my invention, the hollow symmetrical member may be attached to the diaphragm of the receiving device and the element in-

closed by said member projects through the 55 opening of the same to engage the dia- phragm of the talking machine.

In the following I have specifically de- 60 scribed certain forms of my invention, but it will be understood that the invention is not limited to the herein-described particular ap- 65 plications or employment of the same.

Further features and objects of the in- 70 vention will be more fully understood from the following detail description and the accompanying drawings, in which—

Figure 1 is an elevation, partly in vertical central section, showing the use of my in- 75 vention with a telephone receiver and the trans- mitter of an amplifier; and

Fig. 2 shows in detail elevation a cylindri- 80 cal record of a dictating talking machine combined with another form of my in- 85 vention applied to the receiving device of an amplifier.

Referring to Fig. 1, the transmitter 1 of the amplifier is shown mounted on the pedestal 2 suitable for resting on the top of a table or the like. The transmitter 1 is pro- 90 vided with the face portion 3 adapted to re- ceive and support the telephone receiver 4. Preferably, the face portion 3 is provided with the central opening 5 of restricted cross section and also with the peripheral flange 6 of suitable construction to form a seal with 95 the face of the cap 7 of the telephone receiver 4. For convenience of construction, the face portion 3 may be screw-threaded onto the transmitter 1 of the amplifier.

The hollow symmetrical member 8 is 100 shown attached at its base 8^a to the dia- phragm 9 of the amplifier. The opening 10 at the front of the hollow member 8 is of symmetrical cross section and of a pre- 105 determined diameter. The element 11 is pro- vided with the body portion 12, shown as cylindrical, and of a diameter effecting a cer- tain degree of friction against the sides of the opening 10. The face 13 of said body portion 12 is of convex construction or other- 110 wise formed to effect the desired engagement with the diaphragm 14 of telephone receiver 4 for all normal positions of diaphragm 14 assumed during its movement under action of the magnets 15 of the telephone receiver. The base portion of member 11 is preferably 115 similar to the inner walls of the hollow mem- ber 8, to thereby maintain the body portion

- 12 of element 11 in proper alinement relative to the sides of the opening 10 and the diaphragm 14 of telephone receiver 4. The spring 16, combined preferably with a pad 5 17 of felt or the like, serves to effect a gentle but yielding pressure against the element 11 to thereby maintain the desired continuous engagement of the face 13 with the diaphragm 14 of the telephone receiver.
- 10 The operation of such use of my invention is as follows. Upon vibration of the telephone diaphragm 14 the element 11 will be vibrated in correspondence thereto, causing the body portion 12 to reciprocate under 15 definite amplitude and frequency conditions in the opening 10 of hollow member 8, thereby by reason of the frictional engagement between said element 11 and the sides of opening 10, causing the body portion of said 20 hollow member 8 to also vibrate in correspondence and eventually setting up corresponding vibrations in the diaphragm 9 of the amplifier.
- 15 The hollow member 8 may be formed of vulcanite or similar material and the body portion 12 of element 11 may also be of vulcanite but is preferably of amber or like material. I have discovered that amber is a highly advantageous material for the body 25 portion 12 and vulcanite for the hollow member 8, such advantages being apparently derived by reason of the relatively low mechanical friction, the high sensibility of transference of vibration due possibly to 30 static electrical effects, the relatively high susceptibility of engagement of the face 13 of the reciprocated element 11 with the actuated diaphragm of the telephone receiver, etc. In the above form of my invention the 35 arrangement is advantageous for transmission of "conversation" from a telephone system to an amplifier, and to this end a suitable support for the receiver is provided by the fork or bracket 20 shown carried by the 40 device 21 pivoted at 22. The angle of inclination of the telephone receiver is chosen to utilize such portion of the weight of the receiver to cause sufficient pressure of the telephone cap 7 against the face portion 3 of the amplifier transmitter 1, in order to effect 45 the desired seal.
- 45 The pivoted device 21 is for use with the transmitter of the amplifier when it is desired to talk, *i. e.*, dictate, directly into the amplifier, for such purposes as recording a letter or other communication on a talking device to be transcribed later. To this and similar ends, the device is provided with the mouth piece 28, having its inner opening 50 directed toward the acoustic diaphragm 24 disposed in said device 21 so that when the telephone receiver is removed and the device 21 swung on its pivot 22, the acoustic diaphragm 24 is brought into proper relation to 55 the face 13 of the reciprocating element 11.

The "horn" 25 is constructed in correspondence to the face portion 3. Accordingly, upon direct dictating, the sound waves will impinge on acoustic diaphragm 24, causing the element 11 in coaction with the hollow member 8 to transfer the "conversation" to the diaphragm 9 of the amplifier.

In Fig. 2, I have shown the "receiver" 26 of the amplifier in combination with my vibration transferring means and a "dictating" talking machine. As one embodiment of such use, I have indicated the hollow member 27 secured to the diaphragm 28 of the amplifier receiver, *i. e.*, the actuating diaphragm, and the reciprocating element 29 constructed to engage the diaphragm 30 of the dictating talking machine 31 embodying any suitable support for the diaphragm 30 and any approved type of recording stylus 32 and spindle for the "record" cylinder 33. Accordingly, upon vibration of the diaphragm 28 of the amplifier "receiver" 26, the hollow member 27 will be actuated and the vibrations transferred to the reciprocating element 29 and in turn to the diaphragm 30 of the dictating machine. The conversation will be reproduced from the "record" by means of the reproducing sound box of the talking machine, as will be understood.

The above apparatuses are especially useful for recording and reproducing telephone conversation, vocal dictation, speeches, testimony, etc., and other communication in which the intensity of tone is or may be varied within wide limits. Notwithstanding such great variations in intensity I have discovered that the invention effects a practically exact record or reproduction of the original tones and without material loss of clearness and definition.

It will be apparent that my invention is also useful for other types of electro-responsive and acoustically actuated devices for mechanically transferring vibrations of all character, irrespective of amplitude and frequency.

I claim:

1. The combination of vibratable means, vibration responsive means and vibration transferring means comprising a member connected with said vibratable means and a second member in relatively movable frictional relationship with said first named member and controlling said vibration responsive means.

2. The combination of vibratable means, vibration responsive means and vibration transferring means comprising a hollow member controlled by one of said means and a second member extending within and in relatively movable frictional engagement with said hollow member and controlling the other of said means.

3. The combination of an actuating member, vibration responsive means for actuati-

ing said member, a second member, vibration responsive means controlled by said second member and vibration transferring means connecting said actuating member and 5 said second member, said vibration transferring means comprising a movable element controlled by one of said members and a second movable element in sliding frictional relationship with said first named movable element and controlling the movement of the 10 other of said members.

4. The combination with a diaphragm, vibration responsive means for actuating said diaphragm, a member, vibration responsive means controlled by said member and vibration transferring means connecting said diaphragm and said member, said vibration transferring means comprising an element controlled by said diaphragm and a second 15 element in sliding relation with said first named movable element and controlling the movement of said member.

5. The combination with a diaphragm, vibration responsive means for actuating said diaphragm, a second diaphragm, vibration responsive means controlled by said second diaphragm and vibration transferring means connecting said diaphragms, said vibration transferring means comprising an element controlled by said first named diaphragm 20 and a second element in sliding frictional relationship with said first named movable element and controlling the movement of the other of said members.

35 6. The combination with a diaphragm and vibration responsive means for actuating said diaphragm, of a second diaphragm, vibration responsive means controlled by said second diaphragm and vibration transfer- 40 ring means connecting said diaphragms, said transferring means comprising a hollow element provided with an opening and a second element having a body portion projecting through said opening and in sliding frictional relationship with the sides of said opening.

7. The combination with a diaphragm and vibration responsive means for actuating said diaphragm, of a second diaphragm, vibration responsive means controlled by said second diaphragm and vibration transferring means connecting said diaphragms, said transferring means comprising a hollow element provided with an opening, a second 50 element having a body portion projecting through said opening and in sliding frictional relationship with the sides of said opening and yielding means controlling said second element.

60 8. The combination with a diaphragm and vibration responsive means for actuating said diaphragm, of a second diaphragm, vibration responsive means controlled by said second diaphragm and vibration transfer- 65 ring means connecting said diaphragms, said

transferring means comprising a hollow element attached to one of said diaphragms, said hollow element being provided with an opening, a second element having a body portion projecting through said opening in 70 sliding frictional relationship with the sides of said opening and yielding means for effecting engagement of said second element with the other of said diaphragms.

9. The combination of an actuating member, vibration responsive means for actuating said member, a second member, vibration responsive means controlled by said second member and vibration transferring means connecting said actuating member 75 and said second member, said vibration transferring means comprising a movable element controlled by one of said members and a second movable element in sliding frictional relationship with said first named 80 movable element and controlling the movement of the other of said members, said elements having their frictionally engaging portions formed of electrically insulating 85 material.

10. The combination with a diaphragm, vibration responsive means for actuating said diaphragm, a member, vibration responsive means controlled by said member and vibration transferring means connecting 95 said diaphragm and said member, said vibration transferring means comprising an element controlled by said diaphragm and a second element in sliding frictional relation with said first named movable element 100 and controlling the movement of said member, said elements having their frictionally engaging portions formed of electrically insulating material.

11. The combination with a diaphragm 105 and vibration responsive means for actuating said diaphragm, of a second diaphragm, vibration responsive means controlled by said second diaphragm and vibration transferring means connecting said 110 diaphragms, said transferring means comprising a hollow element attached to one of said diaphragms, said hollow element being provided with an opening, a second element having a body portion projecting through 115 said opening in sliding frictional relationship with the sides of said opening and yielding means for effecting engagement of said second element with the other of said diaphragms, the frictionally engaging portions of said elements being formed of dielectric materials.

12. The combination of a transmitting device, a support therefor, a casing, a diaphragm, a mouth piece, said diaphragm and 125 said mouth piece being carried by said casing, means for pivoting said casing on said support, and holding means on said casing adapted to hold a telephone receiver when 130 said casing is in a certain position, said dia-

phragm being brought into operative relation to said transmitting device when said casing is in another certain position.

13. The combination of a transmitting device, a stand therefor, an acoustic diaphragm, a mouth piece, a frame carrying said diaphragm and said mouth piece, means pivotally connecting said frame and said support, a stop for retaining said frame at a certain position, and holding means on said frame for holding a telephone receiver in sealed relation with said transmitting device when said frame is in said certain position, said diaphragm being positioned in said frame to be in operative relation to said transmitting device when said frame is moved out of said certain position into another certain position.

14. The combination of a stand, a transmitting device supported thereby in an inclined upwardly, rearwardly direction, a frame pivoted on said stand, a stop holding said frame in a certain forward position, holding means on said frame effective when said frame is in said certain forward position for holding a telephone receiver in a downwardly inclined position in sealed relation to said transmitting device and a diaphragm positioned in said frame to be brought into operative relation with said transmitting device when said frame is moved to a certain rearward position.

In testimony whereof I have signed this specification.

HARALD SMITH.
